UNITED STATES PATENT OFFICE.

JAMES C. DAWSON, OF WEBSTER GROVES, MISSOURI.

LOOSE-LEAF BINDER.

1,413,904.

Specification of Letters Patent. Patented Apr. 25, 1922.

Application filed May 5, 1919. Serial No. 294,766.

To all whom it may concern:

Be it known that I, JAMES C. DAWSON, a citizen of the United States, and resident of Webster Groves, county of St. Louis, and 5 State of Missouri, have invented certain new and useful Improvements in Loose-Leaf Binders, of which the following is a specification and which are illustrated in the accompanying drawings, forming a part there- 10 of.

The invention relates to loose leaf binders and more particularly to those of that type commonly known as prong binders and which comprise a pair of hingedly connected 15 plates each having curved filing prongs extending toward the other plate.

The object of the invention is to provide a binder of the type described which shall be of increased strength but of inexpensive 20 and durable construction and efficient in operation.

In the accompanying drawings,

Fig. 1 is front view of a loose leaf binder embodying the features of improvement pro- 25 vided by the invention;

Fig. 2 is an end view of the binder showing the parts in closed position;

Fig. 3 is similar to Fig. 2 but shows the parts in open position; and

30 Fig. 4 is a sectional view taken on the line 4-4 of Fig. 1.

The improved binder preferably comprises a pair of sheet metal angle plates 13, 14, hingedly connected along their inner edges, 35 as through a pair of leaf hinges 15 welded onto the plates. In carrying out the invention, the side flanges of the angle plates 13, 14, are formed to comprise upright inner portions 16 and outwardly inclined marginal portions 17. The filing prongs 21, 22, extend between the inclined portions 17 of the plate flanges and increased strength and greater freedom of movement of the sheets (not shown), when filed upon the 40 prongs, are obtained by so inclining the flange portions 17 that they are normal to the prongs.

As is usual in binders of the type illustrated, the filing prongs 21, 22, are arranged 45 in pairs and one of the prongs of each pair is carried by each of the angle plates 13, 14. In the specific construction shown, the prongs 21, 22, are each formed with an enlarged flat head 25 at one end. When so

formed, each prong is attached to the corresponding plate 13, or 14, by extending the prong through an aperture 23, in the inclined portion 17 of the plate and welding the head 25 of the prong to the plate upon the outside. Preferably the inclined portion 17 of each plate 13, 14, is also formed with apertures 24 for receiving the ends of prongs 21 or 22, carried by the other plate, in the closed position of the binder.

A convenient form of latch for holding the parts of the binder in closed position is readily provided if the angle plates 13, 14 are also formed with end flanges 27, 28. As shown, a leaf spring 26 is welded against the end flange 27 of each plate, 13, 14, upon 70 the inside of the same and extends over the other plate. An outwardly facing rounded knob or button 29 mounted upon each leaf spring 26 near the free end of the same, registers with and enters an aperture 30 in the 75 adjacent end flange 28 in the closed position of the parts.

The binder is reenforced and a symmetrical external form is obtained by fitting a 80 filler strip 11 against the upright and inclined portions 16, 17 of each of the angle plates 13, 14, upon the outside of the same. The filler strips 11 may be secured in position by rivets, not shown, passed through the filler strips and through the upright 85 flange portions 16 of the corresponding angle plates. The covers 10 are hingedly united with the filler strips 11 in any well known manner.

I claim as my invention:

1. In a loose leaf binder, in combination, 90 a pair of hingedly connected sheet metal angle plates, one flange of each plate having an upright inner portion, and an inclined marginal portion extending throughout the length of the plate in a radial plane with respect to the axis of the hinged connection between the plates, a curved filing prong extending between the inclined marginal portions of the flanges of the two 100 plates about the said axis as its center of curvature, a filler strip fitted against the upright and inclined portions of said flange of each plate upon the outside of the same and a cover hingedly connected with each of the said filler strips.

2. In a loose leaf binder, in combination, 105 a pair of hingedly connected sheet metal

angle plates having upstanding spaced-apart flanges, an inclined marginal portion on each upstanding flange, a curved filing prong extending between the inclined marginal portions, a cover member having flexible facings secured to its opposite faces and joined at the edge of the member to form a

hinge and a filler strip secured between said facings beyond the hinge and fitted against the upright and inclined portions of one of 10 said angle plates upon the outside of the same.

JAMES C. DAWSON.
